UNITED STATES PATENT OFFICE.

STACY B. HASELTINE, OF CHICAGO, ILLINOIS, ASSIGNOR TO W. H. MINER, INC., OF CHICAGO, ILLINOIS, A CORPORATION OF DELAWARE.

ANTIFRICTION BEARING.

Application filed March 1, 1926. Serial No. 91,328.

This invention relates to anti-friction bearings.

One object of the invention is to provide a simple, practical and efficient anti-friction bearing especially adapted for railway car side bearings, in which the parts are so arranged that the anti-friction element is automatically returned to normal centered position when free from load.

Another object of the invention is to provide a side bearing including a base support adapted to be applied to the truck bolster of a railway car, which support is adapted to accommodate a vertically adjustable bearing plate upon which an anti-friction element is adapted to move to either side of central position with reference to the support, in conjunction with centering and retaining means including a housing which fits over the roller and the base support in such manner as to enclose the same except for the engaging portion of the roller, said housing being movably and detachably connected to said base support and in operative position serving to hold the various parts of the bearing in assembled relation, and to release said parts when said housing is detached from said support.

Other and further objects of the invention will more clearly appear from the description and claims hereinafter following.

In the drawings forming a part of this specification, Fig. 1 is a vertical sectional view taken through the ends of the body and truck bolsters of a railway car, showing my invention, in partial vertical section, in connection therewith. Fig. 2 is a top plan view of the bearing illustrated in Fig. 1, showing the same partly broken away, and detached from the truck bolster. And Fig. 3 is a transverse vertical sectional view of the bearing taken substantially upon the line 3—3 of Fig. 1.

In said drawings, 10 denotes the underside of the body bolster and 11 the upper side of the corresponding truck bolster of a railway car. The improved side bearing is shown as applied to the truck bolster and comprises broadly a base support or mounting A; an adjustable bearing plate assembly B; an anti-friction element C; and centering and retaining means D.

As shown in the drawings, the base support comprises a generally box like member including a bottom plate 20, side walls

21—21, and end walls 22 and 23, the bottom plate member 20 being extended longitudinally outwardly beyond the end walls 22 and 23 as indicated at 24 and 25, or stated in another manner, the end walls 22 and 23 are offset inwardly from the outer extremities of the extensions 24 and 25 of the base support. The support is provided with securing lugs as indicated at 26, said lugs being secured by rivets as indicated at 27 to the truck bolster plate 11. The base support further is provided with ledges or abutments 28—28, extending parallel to the walls 21, one of the abutments being disposed upon the inner side of the end wall 22, and the other abutment being disposed upon the inner side of the end wall 23, the abutments, in conjunction with the side walls of the housing, providing a seat or chamber for the reception of the adjustable bearing plate assembly B. The side walls 21—21 are each provided with apertures adjacent the end walls 22 and 23, preferably above the abutments 28—28, for the insertion of retaining bolts as hereinafter more particularly described.

The adjustable plate assembly B comprises the bearing plate proper indicated at 29, said bearing plate preferably being of hardened steel and of a form and size so as to fit between the side walls 21—21 and the abutments 28—28 as shown in Fig. 1; the means for adjusting the vertical height of the bearing plate comprising a plurality of shims 30, disposed beneath the bearing plate 29 within the chamber provided by the side walls 21—21 and abutments 28—28, vertical adjustment of the plate 29 being accomplished by the substitution, insertion, or removal of shims with respect to the bearing plate.

The anti-friction element C, as shown, is in the form of a plain cylindrical roller adapted to roll upon the bearing plate 29.

The centering and retaining means D comprise a housing indicated as a whole at 31, resilient means 32—32, and retaining bolts 33—33. The housing 31 has side walls 34—34 spaced apart a sufficient distance to fit over the side walls 21—21 of the base support as clearly shown in Fig. 3. Each of said side walls has an inwardly offset centrally disposed extension 35, the extensions 35—35 being adapted to cooperate with the top wall of the housing to provide a cage for the roller in a manner hereinafter more

fully explained. The housing 31 also is provided with end walls 36—36, merging with the side walls, the distance between said end walls being greater than the distance between the end walls 22 and 23 of the base support. Each of the end walls 36 is offset centrally and outwardly as indicated at 37 to provide spring pockets 38—38 which when the device is assembled cooperate with the extensions 24 and 25 of the base support to house the springs 32—32, preferably under a considerable initial or preliminary compression, at the outer sides of the end walls 22 and 23 of the base support, the springs bearing against the end walls of the pockets and against the outer surfaces of the end walls 22 and 23 of the support. The housing 31 is further provided with a top wall 39, said wall being provided with upwardly curved portions 40—40, one of which is disposed on each side of the anti-friction element C, the portions 40—40 in conjunction with the extensions 24 and 25 of the side walls defining a cage having an opening 41 through which the anti-friction element projects. The inner surfaces 141 of the portions 40—40 are adapted to engage the opposite sides of the anti-friction element so that displacement of the roller to either side of central position causes corresponding travel of the housing 31. The engaging surfaces 141 are so arranged that when in assembled relation of the bearing, said surfaces are curved inwardly and disposed above the central axis of the anti-friction element C, said surfaces being straight or vertically arranged as indicated at 42, below the central axis of the roller, when the same is in position upon the bearing plate 29, so that said surfaces permit different vertical positions of the roller resulting from adjustment of the bearing plate, without interfering with the operation of the device. Each of the side walls 35—35 of the housing 31 is provided with horizontally extending longitudinally spaced slots 43—43, and in order to detachably secure the housing 31 in assembled relation with the base support, the retaining bolts 33—33 are employed. The bolts at the opposite ends of the bearing, extend through the horizontally disposed slots in the side walls 35 of the housing, and through the annular openings in the side walls 21—21 of the base support, the bolts being retained in detachable relation by means of ordinary nuts as indicated at 44. In order to prevent accidental detachment of the bolts, a locking plate 45 having turned ends 46—46 is provided so as to engage the bolt heads to prevent turning thereof, and on the opposite side of the bearing a locking plate 47 similar to the plate 45, is provided, which prevents accidental rotation of the nuts 44, while permitting forcible removal thereof so that the housing 31 may be

detached from the base support. With the locking plate arrangement just described, it will be appreciated that the nuts 44 are held upon the bolts in certain definite positions so that the distance between the bolt heads 70 and nuts is such as to provide for free movement between the housing and base support at all times without binding between the parts.

Assuming the device to be in assembled operative condition as illustrated in Fig. 1, when it is desired to adjust the bearing plate, or replace the springs or roller, the housing 31 may be removed by loosening the nuts on the bolts and removing the bolts from the bearing, after which the housing 31 may be lifted vertically thereby releasing the springs 32—32, and releasing the roller, so that the same may be removed from the bearing. When this has been done the bearing plate assembly B may be adjusted by substituting, removing or inserting shims 30, as desired. In reassembling the device new springs may be substituted for the springs 32 if necessary, and a new roller might be provided if desired, the parts being placed in position before reassembling the device. After the bearing plate has been adjusted, or the springs or roller replaced if necessary, the roller is placed upon the bearing plate and the housing partially fitted over the same. The springs are then interposed between the end walls of the pockets 37—37 and the end walls 22 and 23 of the base member, after which the housing is brought down to rest on the latter. The bolts may then be reinserted to hold the housing in position, which in turn maintains the springs and roller in assembled relation with reference to the bearing. After the bearing plate is adjusted vertically, it will be appreciated that the roller will be in a new vertical position with respect to the housing 31, and the changes in position of the roller are accommodated by reason of the shape of the curved engaging faces 41—41 of the curved portions 40—40 as will be appreciated.

When the device is in assembled condition, assuming movement of the anti-friction element C toward the right as indicated in dotted lines, the housing 31 will be carried therewith, this movement being permitted by reason of the provision of the slots 43—43, and during such movement the left hand spring 32 will be compressed between the end wall of the left hand pocket 37, and the wall 22 of the base member, the energy stored in such spring serving to return the housing 31 toward central position, the housing carrying the roller therewith when free from load. Movement of the anti-friction element C toward the left effects a reverse operation of the bearing similar to that just described.

By the above described arrangement, it

will be seen that the housing when in assembled relation not only serves to maintain the parts in normal centered position or to return them thereto, but also protects the working parts of the bearing, and maintains them in assembled relation, the housing being readily detachable for the purpose of making any necessary adjustments.

While I have herein shown and described what I now consider the preferred manner of carrying out the invention, the same is merely illustrative, and I contemplate all changes and modifications that come within the scope of the claims appended hereto.

I claim:

1. In an anti-friction bearing, the combination with a support having a vertically adjustable bearing surface; an anti-friction element adapted to move back and forth on said bearing surface; a housing loosely fitting about said anti-friction element and detachably connected to said support for movement in a horizontal plane substantially constant when in assembled relation and parallel to said support, said housing being provided with surfaces arranged to engage said anti-friction element above the central axis thereof, and being so formed as to permit vertical adjustment of said element and said bearing plate without interference with the operation of said bearing, said support and said housing being provided with oppositely extending rigid portions adjacent their ends; and yieldable means interposed between said oppositely extending portions.

2. In an anti-friction bearing, the combination with a supporting member provided with side and end walls and said support being provided with a bearing plate seat; of a bearing plate associated with said seat; an anti-friction roller adapted to move back and forth upon said bearing plate; of a housing provided with means adapted to engage said anti-friction roller whereby said housing moves with said roller, said housing being provided with side and end walls, said side walls fitting over the side walls of said support; yieldable means interposed between the adjacent end walls of said support and said housing at each end of the bearing; and retaining elements detachably mounted in said support and engaging in slots provided in said housing, whereby movement of said housing with said roller effects actuation of said yieldable means to urge return of said roller toward central position when free from load.

3. In an anti-friction bearing, the combination with a support having side and end walls and being provided with a bearing

surface; and a housing having side and end walls fitting on the outer sides of the side and end walls of said support; yieldable means interposed between the adjacent end walls of said support and said housing; means for detachably connecting said housing with said support; and an anti-friction element adapted to move to either side of central position with reference to said bearing surface and adapted to move said housing to actuate said yieldable means, whereby said anti-friction element is returned toward central position when free from load.

4. In an anti-friction bearing, the combination with a supporting member provided with side and end walls and extensions projecting outwardly beyond said end walls; a bearing plate associated with said support; shims for adjusting the vertical height of said bearing plate; an anti-friction roller adapted to move to either side of central position with reference to said bearing plate; and a housing having means fitting about said roller and adapted to engage the same above the central axis thereof to retain said roller in assembled relation with reference to said support, said housing being provided with side and end walls fitting over the side and end walls of said support; yieldable means interposed between the adjacent end walls of said support and said housing, said yieldable means bearing upon the extensions provided at the ends of said support; and means for detachably connecting said housing with said support so as to permit movement of said housing upon movement of said anti-friction element.

5. In an anti-friction bearing, the combination with a support; of a housing co-operating with said support, said support being provided with spaced end walls, and said housing being provided with oppositely disposed end walls spaced apart a greater distance than the walls on said support, and being adapted to over-lap said latter walls; springs disposed between the walls of said support and said housing; a bearing surface arranged between the walls of said support; and an anti-friction element mounted on said bearing surface, said housing being provided with portions fitting about said anti-friction element above the central axis thereof; and means for detachably connecting said housing to said support for operative movement with respect thereto.

In witness that I claim the foregoing I have hereunto subscribed my name this 26th day of February, 1926.

STACY B. HASELTINE.
